UNITED STATES PATENT OFFICE.

ALVA D. LEE, OF BROOKLINE, MASSACHUSETTS.

REVERBERATORY SMELTING-FURNACE.

No. 888,624.

Specification of Letters Patent.

Patented May 26, 1908.

Application filed May 28, 1907. Serial No. 376,065.

To all whom it may concern:

Be it known that I, ALVA D. LEE, a citizen of the United States of America, and a resident of Brookline, in the county of Norfolk and State of Massachusetts, have invented 5 certain new and useful Improvements in Reverberatory Smelting-Furnaces, of which the following is a specification.

This invention relates to reverberatory 10 smelting furnaces and has for its object the production of such a device which may be made absolutely air tight and operated in this condition under pressure, the furnace being provided with means for regulating 15 the amount of this pressure.

Another object of the invention is to produce a device which may be operated either under a predetermined pressure or which may be readily changed when desired to 20 operate under a vacuum draft.

In order to secure these objects the furnace embodying the features of the present invention is provided with a plurality of tangential burners extending through the walls thereof, 25 said burners being adapted to project a plurality of flames into the cylindrical chamber of said furnace onto the charge contained therein, thereby, while causing an intense heat therein, producing a vortical action of 30 said charge. The centrifugal action thus resulting causes the molten mass contained within the furnace to move around toward the exterior wall thereof and cause a frictional contact between the mass and said 35 projected flames, thus stirring and mixing the charge very effectually. At the same time the vortical action of the charge and flame contained within the chamber produces an eddy in the center of the chamber 40 into which the fine ore dust or fines is thrown down into the molten mass.

The invention consists in certain novel features of construction and arrangement of parts which will be readily understood by 45 reference to the description of the drawings and to the claims hereinafter given.

Of the drawings: Figure 1 represents a sectional plan of a furnace embodying the features of this invention, the cutting plane 50 being on line 1—1 on Fig. 1. Fig. 2 represents a vertical section of the same, the cutting plane being on line 2—2 on Fig. 1. Fig. 3 represents a partial section of the same, the cutting plane being on line 3—3 on Fig. 1. 55 Fig. 4 represents a partial exterior elevation

of one side of the same, showing the mechanism for controlling the valve in the free outlet, and Fig. 5 represents a section through a portion of the furnace showing a burner extending through the wall thereof.

Similar characters designate like parts throughout the several figures of the drawings.

In the drawings, 10 represents a bed of concrete upon which is mounted a cylindrical metal casing supported by means of a plurality of vertical I-beams 12 on the top of which is mounted the charging floor 13. Within the metal casing 11 and between the vertical I-beams 12 of the casing is a lining of 65 firebrick 15 between which and said casing 11 is interposed a layer 14 of sand or similar material. The inner face of the wall 15 is concentric forming a cylindrical chamber 16 into which is charged the ore to be treated 70 through the charging cone 17 passing through the center of the top wall 18 of said furnace. 75

The charging cone 17 is closed by means of the door 19 which may be operated in any well-known manner. Through the casing 11 80 and the linings 14 and 15 therefor are tangentially mounted and downwardly inclined a plurality of oil burners 20 adapted to project a flame into the interior chamber 16 of said furnace. This flame impinges upon the 85 charge contained within the chamber 16 and produces therein a vortical action which is continued as long as the burners continue to operate.

A plurality of burners 20 are used in connection with the furnace either one or more of which may be shut off to regulate the heat within the chamber 16. At one side of the furnace is a flue outlet 21 which extends upwardly and then downwardly, the mouth of which 95 communicates with the cylindrical casing 22 in which is mounted an aspirator 23 which is adapted to operate, by the admission of steam thereto through the valved pipe 24, to produce a vacuum in the casing 22 and thus 100 cause a suction adapted to effect a withdrawal of the volatile gases generated in the chamber 16, these gases passing through the casing 22 into a suitable receptacle 24 containing a suitable liquid 25 through which 105 the gases are obliged to pass beneath a baffle plate 26 to cause a precipitation of any ingredients contained within said gases, all in a well-known manner.

The flue outlet 21 is provided with a hinged 110

valve 27 which is adapted to close the outlet and cause the chamber 16 to be perfectly air tight, thus permitting the furnace to be operated without the admission of air thereto except that which passes through the burners 20 which air will be admitted to the chamber 16 under pressure as is also the oil and steam passing through the burners, the amount of air, steam, and oil passing through said burners being regulated by any suitable means.

When too great a pressure is contained within the chamber 16 the valve 27 will be forced open against the tension of the spring 28 mounted upon the curved threaded rod 29 which has threaded thereto an adjustable member 30 for regulating the tension of said spring. This spring 28 operates against a lever 31 on the end of the pivot of the valve 27. When it is desired to operate the furnace under a vacuum draft the valve 27 may be held in open position by means of the catch 32 engaging with the lever 31 on the pivot of said valve.

A plurality of cylindrical members 33 extend through the walls of the furnace each of these members being provided with a valve 34 which may be closed by means of the milled head 35. The outer end 36 of each of these cylindrical members is closed by means of a sheet of mica which prevents the heat from escaping while at the same time when the valve 34 is opened the operator is afforded an opportunity to inspect the interior of the chamber 16 without opening any orifice to admit air thereto. The walls of the furnace are also provided with a plurality of doors 37, hinged at 38, these doors being adapted to permit the operator to secure access to the interior of the chamber 16 when necessary.

The bottom of the chamber 16 has cut therein an inclined furrow 39 terminating in an opening 40 passing through the firebrick lining 15 of the wall of the furnace into the opening communicating with a tapping outlet 41 of any well-known construction. At a somewhat higher level than the opening 40 is another opening 42 extending through the walls of the furnace, this latter opening 42 being for the purpose of drawing off the slag when ores have been reduced to a molten state. This may be done by opening the doors 37 and pushing the slag over the opening 42 through which the slag is drawn off.

When the slag has been thoroughly removed through the opening 40, the molten metal in the bottom of the furnace is permitted to pass through said opening into any suitable receptacle.

When the burners 20 are in operation the flames will be projected downwardly on top of the ore contained within the furnace and this ore will soon be reduced to a molten state and the action of the flames thereon will produce a vortical action thereon caus-

ing the mass to be moved around the axis of the chamber 16 and sufficiently agitated to cause any metallic globules or particles to be shaken down through the slag to the bottom of the chamber 16. When this has been accomplished the burners 20 will be shut off and the slag removed as heretofore described and then the furnace tapped for the withdrawal of the molten metal.

In the meantime the volatile gases generated by the action of the flames upon the ores will pass through the flue stack 21, the vacuum caused by the aspirator 23 assisting in the withdrawal of these gases. During the centrifugal movement of the molten mass and flames in the furnace an eddy will be formed in the center which will gather therein any of the ore dust or other fine material which material will thereby become a part of the molten mass, thus avoiding the production of flue dust.

As one of the burners operates across the stack at the flue outlet under heavy pressure of steam and air all solid particles are prevented from passing out through said outlet only the gases generated within the furnace being permitted to pass off in this manner. As the solid particles which may accumulate near the flue outlet and endeavor to pass off that way are acted upon by the pressure of steam and air from the burner they are forced to mix with the molten mass and become a part of it.

By means of the burners an absolute control of the mixture entering the furnace is secured so that the operator can produce at will a reducing heat or an oxidizing heat.

The furnace is designed to treat those metals or ores which cannot be thrown down readily except under pressure as, for example, zinc, and also other ores which cannot be volatilized or thrown off except by a vacuum, notably sulfur and arsenic.

While it is true that zinc may be thrown down under a reducing heat without pressure it has been found that much quicker and better results are obtained when under pressure as is provided for in the present invention.

It is obvious from the foregoing description that the furnace shown in the drawings and herein described is peculiarly adapted for use in either manner.

The draft secured by means of the aspirator is very simple and effectual and can be very easily and quickly changed from pressure to a vacuum. By causing the heat generated in the vacuum to rotate in the manner in which it does the heating size or radiation of the furnace is materially increased, thereby causing a great saving in the fuel consumption.

Another great advantage of a furnace of this character is that when the furnace is heated and a molten charge bedded the

operation is continuous, thereby very materially increasing the capacity of the furnace. Again the charge is completely under the control of the operator at all times and he can control the gas to such an extent as to enable him to desulfurize, or carry off volatile metals and when this has been accomplished to reduce the balance and tap off when necessary.

10. The furnace is particularly adapted for smelting copper and lead ores direct, especially high grade ores, while at the same time it is quite as adaptable for the treatment of iron ore and for reducing concentrates.

15. Owing to the large heating surface which a furnace of this character has the massing of the ores as in a blast furnace is avoided and freezing is thus prevented.

20. Another great advantage is that the operator is enabled to gage the fuel needed to insure fluidity of the charge, being able to continually inspect the interior of the furnace and learn from observation just the 25 required amount of fuel necessary to secure the desired results.

25. Owing to the rotating flame which is caused by the tangential position of the burners which project flames tangentially 30 and cause a centrifugal movement of the flames within the chamber 16, these flames being projected under pressure, the heat absorption of the ore is greatly facilitated and the loss by radiation is reduced to a minimum while the time for reduction of the ore is greatly shortened.

35. The furnace is practically a crucible with the heat applied internally rather than externally, and will be found superior for 40 treating high grade steels, and iron, as the phosphorus, sulfur, and other deleterious volatile metals may be fluxed out with the gas mixture and under vacuum exhaust, a point of utmost importance in treating iron 45 or steel. After the metal has been properly melted and fluxed for impurities, it can be put under pressure, and the proper alloys or carbon can be charged into it, giving the most perfect mixture with the most simple 50 mechanical operation of any furnace made.

45. It is especially adapted for casting work. Since the heat may be applied under pressure great fluidity can be had, thus insuring good flow and castings free from blow holes.

55. It practically eliminates all oxygen.

50. From the foregoing description it is believed that the operation and many advantages of a furnace of this class will be thoroughly understood.

60. Having thus described my invention, I claim:

1. In a reverberatory smelting furnace, the combination of a cylindrical walled chamber; a plurality of tangential devices 65 for projecting flames upon the contents of

said chamber and thereby creating a vortical action thereof; and means for making said furnace air tight.

2. In a reverberatory smelting furnace, the combination of a cylindrical walled chamber; a plurality of tangential devices extending through the walls of said chamber for projecting flames upon the contents of said chamber and thereby creating a vortical action thereof; and means for making said 75 furnace air tight.

3. In a reverberatory smelting furnace, the combination of a cylindrical walled chamber; a plurality of tangential devices extending through the walls of said chamber 80 and inclined downwardly toward the center thereof for projecting flames upon the contents of said chamber and thereby creating a vortical action thereof; and means for making said furnace air tight.

4. In a reverberatory smelting furnace, the combination of a cylindrical walled chamber; a plurality of tangential devices extending through the walls of said chamber and inclined downwardly toward the center 90 thereof for projecting flames upon the contents of said chamber and thereby creating a vortical action thereof; an outlet therefrom; and a device for creating a vacuum therein.

5. In a reverberatory smelting furnace, 95 the combination of a cylindrical walled chamber; a plurality of tangential devices for projecting flames upon the contents of said chamber and thereby creating a vortical action thereof; an outlet therefrom; a valve 100 in said outlet; and means for closing said valve.

6. In a reverberatory smelting furnace, the combination of a cylindrical walled chamber; a plurality of tangential devices 105 for projecting flames upon the contents of said chamber and thereby creating a vortical action thereof; an outlet therefrom; a valve in said outlet; means for closing said valve; a charging cone; and a valve to close said cone. 110

7. In a reverberatory smelting furnace, the combination of a cylindrical walled chamber; a plurality of tangential devices for projecting flames upon the contents of said chamber and thereby creating a vortical 115 action thereof; an outlet therefrom; a valve in said outlet; means for closing said valve; a charging cone; a valve to close said cone; and means for preventing the admission of air to said chamber.

8. In a reverberatory smelting furnace, the combination of a cylindrical walled chamber; a plurality of oil burners extending tangentially through the walls thereof means for making said furnace air tight; an outlet from said chamber for the gases generated therein; and a discharge outlet for the molten metal in said chamber. 125

9. In a reverberatory smelting furnace, the combination of a cylindrical walled 130

chamber; a plurality of oil burners extending tangentially through the walls thereof; an outlet from said chamber for the gases generated therein; a discharge outlet for the 5 molten metal in said chamber; and an inclined trough in the bottom of said chamber communicating with said discharge outlet.

10. In a reverberatory smelting furnace, the combination of a cylindrical walled chamber; a plurality of oil burners extending tangentially through the walls of said chamber; and a plurality of valved tubes extending through the walls of said chamber adapted to permit an inspection of the interior 15 thereof.

11. In a reverberatory smelting furnace, the combination of a cylindrical walled chamber; a plurality of oil burners extending tangentially through the walls of said chamber;

ber; an outlet from said chamber for the 20 gases generated therein; a valve in said outlet; and a spring normally closing said valve.

12. In a reverberatory smelting furnace, the combination of a cylindrical walled chamber; a plurality of oil burners extending 25 tangentially through the walls of said chamber; an outlet from said chamber for the gases generated therein; a valve in said outlet; a spring normally closing said valve; and means for regulating the tension of said 30 spring.

Signed by me at Boston, Mass., this 23d day of May, 1907.

ALVA D. LEE.
